Primary Examiner — Austin Murphy

(57) **CLAIM**

I claim the ornamental design for the log handling tool, as shown and described.

DESCRIPTION

FIG. 1 is a perspective view from slightly above the log handling tool showing my new design;

FIG. 2 is a perspective view from slightly below thereof;
FIG. 3 is a right side elevation view, the left side view being a mirror image thereof;

FIG. 4 is a front elevation view thereof;

FIG. 5 is rear elevation view thereof;

FIG. 6 is a top plan view thereof; and,

FIG. 7 is a bottom plan view thereof.
